UNITED STATES PATENT OFFICE.

ANTOINE P. PLAUT, OF FLINT, MICHIGAN, ASSIGNOR OF ONE-HALF TO ROBERTS BRASS MANUFACTURING COMPANY, OF DETROIT, MICHIGAN, A CORPORATION OF MICHIGAN.

FUEL VAPORIZER.

Application filed August 22, 1921, Serial No. 494,360. Renewed October 19, 1923.

The invention relates to fuel vaporizers, and has for its object the provision of a device which is simple in construction and which will vaporize the liquid fuel in the explosive mixture passing therethrough. With this object as well as others in view, the invention resides in the novel features of construction as more fully hereinafter set forth.

In the drawings:

10 Figure 1 is a top plan view of a fuel vaporizer embodying my invention;
15 Figures 2 and 3 are respectively cross sections on the lines 2—2 and 3—3 of Figure 1;
1 is the body of the fuel vaporizer having the spaced inner and outer walls 2 and 3 respectively and the bottom and top walls 4 and 5 respectively at the inlet and outlet ends of the device. These walls inclose a chamber 6 adapted for the passage of a heating fluid, 20 which in the present instance is the exhaust gases from the internal combustion engine to which the device is applied. The chamber 6 is provided with an inlet passageway 15 adapted to be connected to the source of exhaust gases and is provided with an outlet passageway 16 having therein a throttle valve 19 for controlling the flow of exhaust gases through the device. The inner wall 2 forms the passageway 7 adapted for the passage of the explosive mixture of air and liquid fuel and the inlet and outlet ends 8 and 9 of this passageway are of substantially the same cross sectional area as the carburetor outlet and the intake manifold inlet, the portion 30 of the passageway intermediate its ends being enlarged. The inlet end wall 4 has the flange 10 extending inwardly beyond the inner wall 2 to form the ledge 11 upon which any liquid fuel which drops out of the explosive mixture passing through the passageway 7 will rest while the outlet end wall 5 has the tapering surface 12 which tapers in the same direction as that taken by the explosive mixture.

45 Arranged within the enlarged portion of the passageway 7 are the spaced baffle plates 13 which extend transversely of the passageway and connect into the inner wall 2 at their ends. These baffle plates are preferably cast 50 integral with the inner wall so that heat will be more readily conducted thereinto from the

inner wall. The baffle plates diverge from each other in the direction taken by the explosive mixture passing through the device so that in operation the explosive mixture of air 55 and fuel upon being drawn through the passageway 7 will strike the baffle plates as well as the inner wall which being heated will vaporize the particles of fuel thereby forming a more homogeneous mixture. Any particles 60 of fuel which drop out of the mixture passing along the inner wall will finally come to rest upon the ledge 11 which being heated will vaporize these particles. Furthermore, since the cross sectional area of the space between 65 the baffle plates at their upper edges is larger than that between the baffle plates at their lower edges, the velocity of that portion of the mixture of air and fuel which passes between the lower edges of the baffle plates is 70 much less in the space between the upper edges of the baffle plates so that at least some of the particles of fuel will drop back upon the baffle plates which being heated will vaporize these particles after which they will again 75 enter the mixture and pass out of the device.

What I claim as my invention is:

1. In a fuel vaporizer, the combination with a fuel mixture conduit, and means for heating the walls thereof, of a pair of partition walls extending longitudinally within said conduit forming three separate passageways for the fuel mixture, said partitions being in heat conducting contact with said heated walls and being arranged to diverge 80 in the direction of flow of the mixture to progressively enlarge the passageway intermediate said partitions.

2. In a fuel vaporizer, the combination with a fuel mixture conduit having inlet and outlet openings and an enlarged chamber intermediate the same, of a pair of partition walls extending longitudinally of said conduit within said enlarged chamber forming three separate passageways for the fuel mixture, said partitions being in heat conducting contact with said conduit and being arranged to diverge in the direction of flow of said mixture to progressively enlarge the central 95 of said passageways.

3. In a fuel vaporizer, the combination with a vertical cylindrical conduit, having

an inlet opening at the bottom and an outlet opening at the top and an enlarged intermediate cylindrical chamber, a passageway for a heating medium surrounding said conduit, a pair of plates extending throughout the length of said enlarged chamber dividing the same into three passageways, said plates

being integral with said conduit and being spaced closer together at the lower end than at the upper end whereby the central of said 10 passageways is progressively expanded in the direction of flow.

In testimony whereof I affix my signature.

ANTOINE P. PLAUT.
